UNITED STATES PATENT OFFICE

WILLIAM C. HIERING, OF NEWARK, NEW JERSEY, ASSIGNOR TO J. E. MERGOTT CO., OF NEWARK, NEW JERSEY, A CORPORATION OF DELAWARE

BAG FASTENER

Application filed June 20, 1930. Serial No. 462,488.

This invention relates to fastening devices intended especially for use on ladies' hand bags.

Heretofore, in opening a lady's hand bag, it has been necessary to first move the fastening device, with which the bag is equipped, to a position to release the frame members of the bag, and then force the frame members apart manually. Such a procedure, obviously, is inconvenient, and decidedly objectionable in situations when quick access to the contents of the bag may be desired.

It is therefore, an object of this invention to provide a fastening device for hand bags, which, when moved to an unlatching position, will automatically spread the frame members of a hand bag.

Many hand bags are provided with a strap fixed at its end to one side of the bag, for the purpose of receiving a hand to facilitate the carrying of the bag.

This is a convenient manner of carrying a bag, but it is objectionable in that it leaves the fastening device for the bag free to be surreptitiously manipulated while the person carrying the bag may be engrossed in other matters.

It is a further object of the invention to provide means for simultaneously carrying a hand bag and controlling the action of the bag fastening device to prevent the theft of the contents by pickpockets, etc.

These and other objects are attained by the novel construction, combination and arrangement of parts hereinafter described and shown in the accompanying drawings, constituting a material part of this disclosure and in which:

Figure 1 represents a perspective view showing the manner of carrying a hand bag equipped with the invention.

Figure 2 represents a sectional view of a hand bag embodying the invention, the bag being in a closed condition.

Figure 3 represents a sectional view similar to that shown in Figure 2, the bag being in an open condition.

Figure 4 represents a partial sectional view of a detail of the bag fastener.

Figure 5 represents an elevational view of

a spring detent employed in the fastening device.

Referring to the drawings, in Figure 1, there is shown a hand bag having channeled frame members 6 and 7, hingedly connected, and attached to bag material 21. Attached to one side of the bag is a strap 8 designed to receive a hand for carrying the bag as shown in Figure 1.

Passing through the material 21 of the bag and supported by frame member 7 is a pin 9, provided with an escutcheon 10, and having a reduced portion 11 having opposed flat sides as shown in Figure 4, the reduced portion 11 being integral with a conical or wedge shaped head 12, the latter having a pair of oppositely disposed notches 13 designed to receive a detent 16 projecting downwardly through an aperture in the bottom of the channel of frame member 6. The detent 16 is integral with a resilient bar 17 riveted to the frame member 6 at 18.

Riveted at 23 to the bottom of the channel of frame member 7 is a plate 15 having a recess 22 in which is positioned a spring 14, the latter being in the form of a wire and having its ends passing through apertures in frame member 7.

The spring 14 bears constantly against the reduced portion 11 of pin 9, and urges the pin so that there will normally be one of the flat faces of reduced portion 11 in engagement with the spring 14. When the pin 9 is in such a position the notches 13 in the head 12 are in position to receive the detent 16.

Now, when pin 9 is rotated to force the detent 16 out of the notch 13 to unlatch the frame members, the detent bears down on the tapered portion of the head between the oppositely disposed notches 13, and automatically spreads the frame members 6 and 7 apart; thus obviating the necessity of manually forcing such members apart.

Pivotedly connected to pin 9 is a ring 19, to which is rigidly attached a flexible strap 20, the latter being designed to normally lie over the strap 8. When it is desired to open or close the bag, the fastening device is ma-

nipulated by means of the ring 19 and the strap.

When the bag is closed, the strap will lie over strap 8, and thus prevent unauthorized opening of the bag. It will be also noted that whenever the strap 20 overlies the strap 8, one of the notches 13 in head 12 will be in a position to receive the detent 16.

From the above description it will be seen 10 that I have provided a fastening device which will automatically spread the frame members of a hand bag to assist in the opening thereof; and also there is provided a simple means for manipulating the fastening device at the 15 same time serving to prevent the theft of the contents of the bag.

The foregoing disclosure is to be regarded as descriptive and illustrative only, and not as restrictive or limitative, of the invention, 20 of which, obviously, an embodiment may be constructed including modifications without departing from the general scope herein indicated and denoted in the appended claims.

Having thus described my invention, what 25 I claim as new and desire to secure by Letters Patent, is:

1. In a hand bag having a pair of hingedly connected frame members, a fastening device comprising, a pin rotatably supported by one 30 of the frame members, said pin having a conical head provided with a pair of slots, and a resilient detent mounted on the other frame member, said detent entering one of the slots to hold the members together, and adapted 35 to engage the conical head to spread the members apart.

2. In a hand bag having a pair of hingedly connected frame members, a fastening device comprising a pin rotatably supported by one 40 of the members, said pin having a wedge-shaped head provided with a pair of slots, and a resilient detent positioned to enter one of the slots to hold the members together or 45 to engage the wedge shaped head to spread the members apart.

3. In combination with a pair of hingedly connected frame members, a fastening device comprising a pin rotatably supported by one 50 of the members, and a resilient detent mounted on the other frame member, said pin having a wedge shaped head provided with means engageable by the detent to hold the members together, said detent engaging the wedge shaped head in a certain position 55 thereof to force the members apart.

4. A fastening device comprising a rotatably mounted pin having a wedge shaped head, a resilient detent, and means on the head engageable by the detent to hold the head and detent together, said detent engaging the wedge shaped head in a certain position 60 thereof to urge them apart.

This specification signed this 16th day of June, 1930.

65 WILLIAM C. HIERING.
